SPARK PRODUCING BAR FOR IGNITING FIRE MAKING MATERIAL

Vahe Arifian, Livingston, N.J., assignor to Sparky Lite
Company, Livingston, N.J., a copartnership of New
Jersey

Filed Jan. 21, 1969, Ser. No. 15,430

Term of patent 14 years

Int. Cl. D27—05

U.S. Cl. D48—27

FIG. 1

FIG. 2

FIG. 3

FIG. 4

FIG. 1 is a top plan view of a spark producing bar for igniting fire making materials, showing my new design; FIG. 2 is a side elevation thereof;

FIG. 3 is an end elevation thereof; and

FIG. 4 is an end elevation as seen from the left of FIG. 2.

I claim:

The ornamental design for spark producing bar for igniting fire making material, as shown.
